UNITED STATES PATENT OFFICE.

WILLIAM S. JONES, OF OWOSSO, MICHIGAN, ASSIGNOR TO L. E. WOODWARD,
OF SAME PLACE.

DESIGN FOR A BURIAL-CASKET.

SPECIFICATION forming part of Design No. 26,754, dated March 9, 1897.

Application filed January 11, 1897. Serial No. 618,882. Term of patent 14 years.

To all whom it may concern:

Be it known that I, WILLIAM S. JONES, a citizen of the United States, residing at Owosso, county of Shiawassee, State of Michigan, have 5 invented and produced a new and original Design for a Burial-Casket, of which the following is a specification, reference being had to the accompanying drawings, showing a part thereof.

1. In the drawings, Figure 1 is a view in side elevation showing my design with the cover closed. Fig. 2 is a similar view with a portion of the cover removed. Fig. 3 is a plan view. Fig. 4 is an end view, and Fig. 5 is an 15 end view showing a modification in the illustration of my design.

The leading feature of my design consists in a casket-cover of circular outline in cross-section, the same being formed on the arc of 20 a circle in cross-section, the ends of the cover being also formed with a curved outline longitudinally of the casket. This cover rests upon a base, the meeting edges of the base and cover being preferably provided with 25 molding, the molding being preferably offset between the ends of the casket, the body being preferably provided with pilasters at the extremities of the offset portions of the molding, although my design is not limited solely 30 to the use of the offset molding and pilasters.

A represents the body of the casket.

B represents the foot portion of the cover, and B' the head portion of the cover, which

head portion may be removable. These cover portions are of circular form in their outer 35 contour across the casket from side to side, as indicated more particularly in Figs. 4 and 5, while also the extremities of the cover are of circular outline lengthwise of the casket, as represented in Figs. 1 and 2. The body of 40 the casket is also of circular form in the outer contour of its extremities. Below the head portion of the cover is a panel portion B², having a flat upper portion B³ for a nameplate.

In Figs. 1 to 4, C C represent portions of the molding, offset at the sides of the casket intermediate its ends, and D D represent vertical pilasters rising from the base of the casket to the extremities of the offset portions of the molding. In Fig. 5, however, the pilasters are omitted and the molding is not offset intermediate the ends of the casket, the molding C' simply extending around 55 at the meeting edges of the base of the cover portions of the casket.

What I claim is—

The design for a burial-casket, as herein shown and described.

In testimony whereof I sign this specification in the presence of two witnesses.

WILLIAM S. JONES.
